CLAIM

The ornamental design for a bevel gauge, as shown and described.

DESCRIPTION

FIG. 1 is a front, top, right side isometric perspective view of a bevel gauge in accordance with my design;
FIG. 2 is a front elevation view thereof;
FIG. 3 is a back elevation view thereof;
FIG. 4 is a right side view thereof;
FIG. 5 is a left side view thereof;
FIG. 6 is a top plan view thereof;
FIG. 7 is a bottom plan view thereof;
FIG. 8 is a front, top, right side isometric perspective view of an alternative embodiment of a bevel gauge;
FIG. 9 is a front elevation view thereof;
FIG. 10 is a back elevation view thereof;
FIG. 11 is a right side view thereof;
FIG. 12 is a left side view thereof;
FIG. 13 is a top plan view thereof; and,
FIG. 14 is a bottom plan view thereof.
The broken lines illustrate portions of the bevel gauge which form no part of the claimed design.
